CLAIM

The ornamental design for a vacuum cleaner, as shown and described.

DESCRIPTION

FIG. 1 is a top, front and right-side perspective view of a vacuum cleaner showing my new design;

FIG. 2 is a front view thereof;

FIG. 3 is a right-side view thereof; the left side being a mirror image;

FIG. 4 is a rear view thereof; and,

FIG. 5 is a top view thereof.

The details shown in broken lines form no part of the claimed design.
